US0D1036502S

(12) **United States Design Patent** (10) **Patent No.:** **US D1,036,502 S**
(45) **Date of Patent:** **** Jul. 23, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventor: **YunJae Kim**, San Francisco, CA (US)

(73) Assignee: **Apple Inc.**, Cupertino, CA (US)

(**) Term: **15 Years**

(21) Appl. No.: **29/892,071**

(22) Filed: **May 12, 2023**

Related U.S. Application Data

(63) Continuation of application No. 29/834,633, filed on Apr. 13, 2022, now Pat. No. Des. 990,515, which is a continuation of application No. 29/738,913, filed on Jun. 21, 2020, now Pat. No. Des. 949,185.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
